(57) **CLAIM**

The ornamental design for a lure cone as shown and described.

DESCRIPTION

FIG. 1 is a top-right perspective view of the design for a lure cone;

FIG. 2 is a bottom-right perspective view thereof;

FIG. 3 is a front elevation view thereof;

FIG. 4 is a left elevation view thereof, the right elevation and the back elevation being mirror images;

FIG. 5 is a top plan view thereof; and,

FIG. 6 is a bottom plan view thereof.

The shading lines shown in the drawings represent the approximate three-dimensional contour of the design and are not intended to indicate surface decoration.
